Primary Examiner — Elizabeth J Oswecki(74) *Attorney, Agent, or Firm* — Womble Bond Dickinson (US) LLP(57) **CLAIM**

The ornamental design for a holiday ornament, as shown and described.

DESCRIPTION

FIG. 1 is a top front perspective view of a holiday ornament showing my new design;

FIG. 2 is a front view thereof;

FIG. 3 is a left side view thereof;

FIG. 4 is a right side view thereof;

FIG. 5 is a rear view thereof;

FIG. 6 is a top view thereof; and,

FIG. 7 is a bottom view thereof.

The dash-dot lines in FIGS. 1 and 6 represent boundaries of the claimed surface, the boundaries forming no part of the claimed design.

1 Claim, 7 Drawing Sheets(56)
